4 Claims. (Cl. 98—33)

1

This invention relates to method and apparatus for treating air, and more particularly deals with adsorption apparatus and method which may be used advantageously for conditioning air in workrooms and the like by removing therefrom vapors resulting from manufacturing operations and by controlling the humidity of the atmosphere according to the requirements in each case.

In the printing of webs of Cellophane paper and the like at high speeds, and particularly where multicolor printing is being done, it is of utmost importance that the humidity of the atmosphere in the workroom and the moisture content of the material being printed be controlled within close limits. It is also necessary that the printing presses or apparatus, which are generally of the gravure type, be open rather than enclosed in order to facilitate the keeping of the successive impressions in proper register by the operator. In other words, it is requisite that the operator have free access at all times to the mechanism controlling the register of the successive printing units, as otherwise the resulting multicolor print will be off-register and unsalable. This feature is of particular importance in the printing of continuous webs of material such as Cellophane and paper, since the removal of a portion of the printed web from the finished roll of material due to off-register is a costly operation, wasteful of time, labor and material.

Inks used in gravure printing are generally large in volatile solvents. These solvents include water immiscible solvents such as coal tar and petroleum fractions and also water miscible solvents such as ethers, ketones, alcohols and esters. Since it is requisite that the printing presses be open and readily accessible to the operator, it is necessary to remove large volumes of air carrying solvent vapors from the workroom. Since it is also necessary that humidity conditions be maintained within close limits in the workroom and in the storage rooms wherein the material to be printed is stored, the exhausting of such large volumes of air from the workroom in order to maintain proper working conditions and avoid fire and explosion hazards is extremely costly and wasteful unless it is possible to remove from the air exhausted from the workrooms the solvent vapors contained therein and to return the denuded air to the workrooms free from solvent vapors and at substantially the same temperature and humidity as when exhausted therefrom.

According to the present invention, a system of operation has been developed which makes it possible effectively to control the temperature and

2

humidity of the air in the workrooms at all times and to maintain the atmosphere in the workrooms substantially free from solvent vapors in a concentration which would prove unhealthful, or which would create a fire or explosion hazard.

The present invention will be fully understood from the following description taken in connection with the annexed drawings, wherein:

Fig. 1 is a diagrammatic view of a system for circulating air through a workroom and for maintaining the air at predetermined temperature, humidity and solvent vapor concentration;

Fig. 2 is an elevational view, partly broken away, of an adsorber which may be employed in the system of Fig. 1;

Fig. 3 is an elevational view, partly broken away, illustrating a second type of adsorber which may be employed in the system of Fig. 1;

Fig. 4 is an elevational view, partly broken away, of a third type of adsorber which may be employed in the system illustrated in Fig. 1;

Fig. 5 is an elevational view, partly broken away, of a fourth type of adsorber which may be used in the system illustrated in Fig. 1; and

Fig. 6 diagrammatically illustrates an operating scheme such as may be employed in the operation of the system illustrated in Fig. 1 using any of the several types of adsorber illustrated in Figs. 2, 3, 4 and 5.

Referring to the drawings in detail, in Fig. 1, 10 is a workroom such as may be employed for printing Cellophane or paper in multicolor gravure presses at high speeds. 11 is a filter and flame arrestor adapted to remove dust, lint, scrap, and the like, from the air exhausted from the workroom 10 and to prevent the propagation of fire which might originate accidentally in the workroom. 12 is an exhaust fan for removing air from the workroom 10. 13a, 13b, 13c, and 13d are adsorbers provided with a plurality of beds of adsorbent 14 such as activated carbon and connected through conduits 15a, 15b, 15c, and 15d, and valves 16a, 16b, 16c, and 16d to the distributing headers 17a, 17b, 17c, and 17d on the adsorbers 13a, 13b, 13c, and 13d, and the duct 18 which carries the air exhausted from the workroom 10 by the exhaust fan 12.

Air exhausted from the workroom 10 by the exhaust fan 12 enters the adsorbers 13a, 13b, 13c, and 13d through the headers 17a, 17b, 17c, and 17d, respectively, and is discharged from the adsorbers 13a, 13b, 13c, and 13d through the exhaust lines 19a, 19b, 19c, and 19d, respectively, which are connected through conduits 20a, 20b, 20c, and 20d, and the valves 21a, 21b, 21c, and 21d

to the duct 22 connected with a pressure blower 23 which discharges into a humidity and temperature control chamber 24 and thence to the workroom 10.

A pressure blower 25 discharges fresh air at ambient temperature through a heat exchanger 26 and duct 27 into adsorbers 13a, 13b, 13c, and 13d, respectively, through valves 28a, 28b, 28c, and 28d, conduits 15a, 15b, 15c, and 15d, and headers 17a, 17b, 17c, and 17d, the latter being connected, respectively, to adsorbers 13a, 13b, 13c, and 13d. Air discharged by pressure blower 25 and entering the adsorbers 13a, 13b, 13c, and 13d is discharged, respectively, through valves 29a, 29b, 29c, and 29d.

Steam from a source not shown is admitted into adsorbers 13a, 13b, 13c, and 13d through valves 30a, 30b, 30c, and 30d, respectively, and distillate from the adsorbers 13a, 13b, 13c, and 13d is removed through valves 31a, 31b, 31c, and 31d conduits 32a, 32b, 32c, and 32d, respectively, and caused to flow into conduit 33, and thence into the condenser 34. Water enters the condenser 34 through line 35 and valve 36 and leaves through line 37. Condensate flows out of the condenser through line 38 into decanter 39 from which water immiscible liquid is removed through line 40 and water miscible liquid and condensate through line 41 provided with a gooseneck 42.

In use, the system illustrated in Fig. 1 operates as follows:

The adsorbers 13a, 13b, 13c, and 13d are intended to operate in successive cycles of adsorption, steaming, and drying and cooling. Two of the adsorbers are maintained in the adsorption cycle at all times, while one of the other two adsorbers will be in the steaming cycle and the fourth will be in the drying and cooling cycle. The operation of the adsorbers in the adsorption cycle must be regulated in such manner that one is only half saturated when the other is fully saturated.

Assuming that the system has been in operation for some time, the status of the four adsorbers shown might be the following:

Adsorber 13a	Half saturated
Adsorber 13b	Drying and cooling
Adsorber 13c	Steaming
Adsorber 13d	Fully saturated

At this point, the blower 25 is stopped and the valves 28b and 29b on adsorber 13b are shut off. Valves 21b and 16b are then opened thus permitting air exhausted by the fan 12 from the workroom 10 and discharged through duct 18 to enter the adsorber 13b through valve 16b, conduit 15b, and header 17b, thence through the beds of adsorbent 14, the outlet 19b, the conduit 20b, and valve 21b into the duct 22 and through the pressure blower 23 and the humidity and temperature control chamber 24 into the workroom 10.

Immediately after opening the valves 21b and 16b on adsorber 13b, the valves 16d and 21d are shut thus stopping the flow of air through adsorber 13d. At this point adsorber 13a will be half saturated, adsorber 13b will have entered the adsorption cycle, adsorber 13c will be completing the steaming cycle, and adsorber 13d will be fully saturated and ready to be steamed. To this end, valves 30c and 31c on adsorber 13c are shut and the valves 31d and 30d on adsorber 13d will be opened. This places the adsorber 13c in condition to be dried and cooled and causes the adsorber 13d to enter in the steaming cycle.

Steam flowing into adsorber 13d through valve 30d will flow downwardly through the lower bed 14 and thence outwardly through the valve 31d into the line 33 and the condenser 34 carrying with it vapors of solvents removed by the lower bed of the adsorber 13d while said adsorber was in the steaming cycle. At the same time, steam entering the adsorber 13d through the valve 30d will flow upwardly through the upper bed 14 and thence through the header 17d into the lower portion of the adsorber 13d and from there through valve 31d into the line 33 and the condenser 34.

Having placed the adsorber 13d in the steaming cycle, the next step is to place the adsorber 13c in the drying and cooling cycle. To this end, valve 29c and valve 28c are opened, steam is caused to flow through the heat interchanger 26, and the blower 25 is placed in motion. Air discharged by the blower 25 will be heated in passing through the heat interchanger 26 and will then flow through duct 27, valve 28c, conduit 15c, and header 17c into the top and bottom portions of the adsorber 13c. The warm air will pass downwardly through the upper bed of adsorbent and upwardly through the lower bed of adsorbent, and thence outwardly through the outlet 19c and the valve 29c and will be discharged into the atmosphere. This condition will continue until the temperature rise in the beds of adsorbent is sharp and steady and indicates that the beds of adsorbent are fully dried. At that point the steam flowing into heat interchanger 26 is shut off and the blower 25 is continued in movement until the temperature of the beds in the adsorber 13c has dropped to substantially room temperature.

The cycles of operation of the several adsorbers are so planned, that at this point, when the adsorber 13c is once again ready to enter the adsorption cycle, the adsorber 13a will have reached saturation, the adsorber 13d will have reached the end of the steaming cycle, and the adsorber 13b will be half through the adsorption cycle. Thereupon the flowing of air to be treated is begun through adsorber 13c and ceased in adsorber 13a. At the same time adsorber 13d passes from the steaming cycle into the drying and cooling cycle, and the adsorber 13a enters the steaming cycle. This general scheme of operation will be further described hereinafter in connection with Fig. 6.

Referring now to Fig. 2, 43 is an adsorber supported on a skirt 44 and provided with an upper bed 45 and a lower bed 46. Each of the beds is supported on an angle iron ring 47 and comprises a foraminous plate 48 and a wire mesh screen 49. The dome is provided with a manhole 50 through which adsorbent may be loaded to form the top bed 45 and the body of the adsorber is provided with a manhole 51 through which the adsorbent may be loaded to form the bottom bed 46. The manhole 52 serves to empty the upper bed and the manhole 53 serves to empty the lower bed. A steam distributor 54 is provided intermediate the beds 45 and 46 and the flow of steam thereto from a source not shown is controlled by the valve 55. A header 56 connects the upper portion of the adsorber with the bottom portion thereof, and is provided with a conduit 57 provided with a valve 58 and with a conduit 59 provided with a valve 60. On the shell of the adsorber intermediate the beds 45 and 46 is provided a conduit 61 provided with a valve 62, and the conduit 61 is provided with a

branch conduit 63 provided with a valve 64. At the bottom of the adsorber there is a trap 65 provided with a valve 66 and a line 67 for removing distillate, and also provided with a valve 68 and a line 69 for the removal of condensate and for draining sludge from the bottom of the trap 65.

In operation, air to be treated enters the adsorber through valve 58, conduit 57, and header 56, traverses the bed 45 downwardly and the bed 46 upwardly and exits through conduit 61 and valve 62. During the steaming cycle, steam enters the distributor 54 through valve 55 and flows upwardly through bed 45 and downwardly through bed 46. The steam flowing upwardly through bed 45 leaves the adsorber through header 56 and enters the bottom portion of the adsorber where it commingles with the steam flowing downwardly through bed 46. The distillate leaves the adsorber through valve 66 and distillate line 67 which are connected to the trap 65. During the drying and cooling cycle air enters the adsorber through valve 60, conduit 59, and header 56, flows downwardly through bed 45 and upwardly through bed 46, and exits through conduit 61, branch conduit 63, and valve 64.

Fig. 3 illustrates an adsorber 70 supported on a skirt 71 and provided with adsorbent beds 72, 73, and 74, each of which is supported on an angle iron ring 75 and comprises a foraminous plate 76 and a wire mesh screen 77. The adsorber is provided with manholes 78, 79 and 80 intended for loading adsorbent to form beds 72, 73, and 74, respectively, and is further provided with manholes 81, 82, and 83 intended to empty the beds 72, 73, and 74, respectively. Air to be treated enters the adsorber through valve 84, conduit 85, and header 86 and flows upwardly through bed 73 and downwardly through beds 72 and 74. That portion of the air which flowed upwardly through bed 73 commingles with that portion of the air which flowed downwardly through bed 72 and exits through the upper connection of the header 87, and that portion of the air which flowed downwardly through bed 74 exits through the lower connection of the header 87. All of the treated air is exhausted through the valve 88.

During the steaming cycle, steam is introduced through valve 89 into the header 87 and flows upwardly through beds 72 and 74 and downwardly through bed 73. The distillate of beds 73 and 74 commingles and exits through the lower connection of the header 86 and the distillate from bed 72 exits from the upper connection of the header 86, and the whole is exhausted through valve 90.

During the drying and cooling cycle, air enters through the valve 91 and is distributed by the header 86. It flows downwardly through bed 72 and bed 74 and upwardly through bed 83. Those portions of the air flowing upwardly through bed 73 and downwardly through bed 72 commingle and exit together through the upper connection of the header 87 and that portion of the air which flows downwardly through bed 74 exits through the lower connection of the header 87. The whole is exhausted from the adsorber through valve 92 associated with header 87.

The adsorber is provided with a trap 93 provided with a drain 94 and a valve 95.

Fig. 4 illustrates an adsorber 96 supported on a skirt 97 and provided with beds of adsorbent 98 and 99 each of which is supported on the shell 100 of the adsorber and the center riser 101 by means of the angles 102 and 103. Each bed com-

prises a foraminous plate 104 and a wire mesh screen 105.

The body of the adsorber is provided with manholes 106 and 107 which serve to permit loading of the adsorbent to form the beds and with manholes 108 and 109 which serve to empty the beds. During the adsorption cycle, air to be treated enters the adsorber through valve 110 and conduit 111 which connects the bottom of the adsorber and flows in part upwardly through bed 99 and in part upwardly through riser 101 and downwardly through bed 98 and both portions exit together through conduit 112 and valve 113.

In the steaming cycle, steam enters the steam distributor 114 through a steam feed line 115 provided with a valve 116 and flows downwardly through bed 99 into the bottom portion of the adsorber and upwardly through bed 98 and then downwardly through riser 101 through which it flows to the bottom portion of the adsorber. The distillate line 117 provided with valve 118 is connected to trap 119. A drain line 120 provided with a valve 121 is also connected to the trap 119 and serves to remove condensate and sludge from the bottom of the adsorber.

During the drying and cooling cycle air enters the adsorber through valve 122 and conduit 111 and is distributed within the adsorber in the same manner as the air to be treated is distributed during the adsorption cycle. The drying and cooling air flows out of the adsorber through conduit 112 and valve 123.

In Fig. 5 is illustrated an adsorber 124 supported on a skirt 125 and provided with beds of adsorbent 126, 127, and 128. Bed 126 is supported on the shell 129 of the adsorber by an angle 130 and comprises a foraminous plate 131 and a wire mesh screen 132. The beds 127 and 128 are each supported by angles 133 on the shell 129 of the adsorber and by angles 134 on the riser 135.

The body of the adsorber is provided with manholes 136, 137, and 138 intended to serve for charging adsorbent to form the beds 126, 127, and 128, respectively, and the manholes 139, 140, and 141 are intended to empty the beds 126, 127, and 128, respectively.

Air to be treated enters the adsorber through valve 142 and header 143 and flows downwardly through beds 126 and 128 and upwardly through bed 127. The portion flowing downwardly through bed 126 and the portion flowing upwardly through bed 127 commingle within the space between these two beds and then flow downwardly through the riser 135 to the bottom of the adsorber. At this point the portion flowing upwardly through bed 127 and the portion flowing downwardly through bed 126 commingle with the portion flowing downwardly through bed 128 and the whole exits through conduit 144 and valve 145.

During the steaming cycle steam enters through valve 146 and flows into the adsorber through conduit 144. One-third of the steam entering the adsorber through conduit 144 will flow upwardly through bed 128 and thence into conduit 143 and two-thirds of the steam entering the adsorber through conduit 144 will flow upwardly through riser 135 into the space between the beds 126 and 127 and half of it will then flow upwardly through bed 126 and into conduit 143 and the other half will flow downwardly through bed 127 into the conduit 143. The distillate will exit from conduit 143 through valve 147.

During the drying and cooling cycle air will enter through valve 148 and header 143 and will travel through the adsorber in the same manner

as the air to be treated travels in the adsorption cycle. The drying and cooling air is exhausted from the adsorber through conduit 144 and valve 149.

Those skilled in the art will understand that while the flow of drying and cooling air has been indicated in each case to be in the same direction as the flow of air to be treated, the apparatus and method of the present invention are not limited in that sense, since the drying and cooling air could be passed through the adsorber countercurrent to the flow of air to be treated with equal satisfaction. Likewise, those skilled in the art will understand that in the case of the adsorbers illustrated in Fig. 3 and Fig. 5, the flow of steam may be reversed without materially influencing the ultimate results. Generally speaking, it is preferred practice to have the steam flow in a direction opposite to the direction of flow of the air to be treated, but this is not requisite. The direction of flow of each of the fluids passed through an adsorber is influenced primarily by local conditions and individual preference.

The operating scheme illustrated in Fig. 6 shows the relative operating cycle of each of four adsorbers in a typical system. The adsorbers are numbered I, II, III and IV, and the characters A, B, C, D, E, F, G, H, J, and K are intended to indicate intervals of time. In the specific instance illustrated in Fig. 6 each of the time intervals A, B, C, D, E, F, G, H, J, and K is equivalent to 20 minutes; therefore, in the case of adsorber I, for example, it will adsorb 40 minutes (A and B), it will steam 20 minutes (C), and it will dry and cool 20 minutes (D).

It will be noted from Fig. 6 that during the time interval A adsorber I and adsorber III are in the adsorption cycle, adsorber II is in the steaming cycle, and adsorber IV is in the drying and cooling cycle. Likewise, in the time interval B the adsorbers I and IV are in the adsorption cycle, the adsorber II is in the drying and cooling cycle, and the adsorber III is in the steaming cycle. It will be noted, therefore, that adsorber I is in the first stage or first lap of the adsorption cycle during the time interval A while the adsorber III is in the last stage or second lap of the adsorption cycle, while during the time interval B the adsorber I is in the last stage or second lap of the adsorption cycle while the adsorber IV is in the initial stage or first lap of the adsorption cycle. It will be noted, in addition, that at no time in the operation of the system illustrated in Fig. 6 are more or less than two adsorbers in the adsorption cycle, nor more than one adsorber in the steaming cycle or in the drying cycle.

Referring back to Fig. 1, fresh air is admitted to the section of the pressure blower 23 through conduit 150 provided with flow regulator 151, and is thus mixed with process air in passing through said pressure blower 23. The humidity and temperature control chamber 24 is intended for the purpose of controlling the temperature and the humidity of the air returned to the workroom 10 by the pressure blower 23 after it has been freed of solvent vapors in passing through the adsorption apparatus which forms part of the overall system in admixture with make-up air entering through conduit 150. This is accomplished by adding moisture to the air (as with a spray of water or steam) under controlled conditions or by removing moisture therefrom (as by refrigeration or adsorption), and by increasing or decreasing the temperature as might be necessary. However, the details of construction and opera-

tion of the humidity and temperature control chamber 24 do not form a part of the present invention and need not be described in detail herein. It will suffice to state that the humidity and temperature control chamber 24 operates automatically as an integral part of the system illustrated in Fig. 1 wherein all of the individual operations are automatically controlled by suitable instruments to form a coordinated process. The method of the present invention can only operate successfully under such coordinated conditions since it is imperative that the concentration of moisture and of solvent vapor in the atmosphere of the workroom, as well as the temperature of the atmosphere, be maintained in a definite predetermined relationship in order to insure proper operative conditions not only from the point of view of health, fire and explosion hazards, but also from the point of view of production, efficiency and economy as reflected by accuracy of register in high speed multicolor printing of the web of Cellophane or paper or the like being processed in the workroom 10.

It will be understood that while there have been described herein certain specific embodiments of the present invention, it is not intended that this invention be limited to the specific details of construction, arrangement of parts, procedures, proportions, times and materials herein described or illustrated in the drawings, in view of the fact that this invention is susceptible to modifications according to individual preference and conditions without departing from the spirit of this disclosure and the scope of the appended claims.

The structure of the adsorption units herein described is claimed in copending application Serial No. 508,518, filed November 1, 1943, as a division hereof, and the adsorption method herein described is claimed in copending application Serial No. 508,519, filed November 1, 1943, as a division hereof.

I claim:

1 claim.

1. The method of continuously maintaining predetermined conditions of temperature, humidity and solvent vapor content in the atmosphere of an enclosure wherein said solvent is used comprising, exhausting atmospheric air from the enclosure, removing solvent content from said air in a first adsorber of a bank of adsorbers while simultaneously subjecting a second adsorber to steam, removing solvent from said atmosphere in a third adsorber and drying and cooling a fourth adsorber, all in a first cycle; then removing solvent content of said air as withdrawn from said enclosure in said first adsorber, drying and cooling said second adsorber, subjecting said third adsorber to steam and removing solvent content from said air as withdrawn from said enclosure in said fourth adsorber, all in a second cycle, then subjecting said first adsorber to steam, removing solvent content from said air as withdrawn from said enclosure in said second adsorber, drying and cooling said third adsorber and removing solvent content from said air as withdrawn from said enclosure in said fourth adsorber; then drying and cooling said first adsorber, removing solvent content from said air as withdrawn from said enclosure in said second adsorber and in said third adsorber, subjecting said fourth adsorber to steam, all in a fourth cycle; and continuously during each of said cycles removing said treated air from two of said adsorbers, establishing predetermined conditions of temperature and hu-

humidity of said treated air, and then returning said air to said enclosure.

2. The method of continuously maintaining predetermined conditions of temperature, humidity and solvent vapor content in the atmosphere of an enclosure wherein said solvent is used comprising, exhausting atmospheric air from the enclosure, removing solvent content from said air in a first adsorber of a bank of adsorbers while simultaneously subjecting a second adsorber to steam, removing solvent from said atmosphere in a third adsorber and drying and cooling a fourth adsorber, all in a first cycle; then removing solvent content of said air as withdrawn from said enclosure in said first adsorber, drying and cooling said second adsorber, subjecting said third adsorber to steam and removing solvent content from said air as withdrawn from said enclosure in said fourth adsorber, all in a second cycle, then subjecting said first adsorber to steam, removing solvent content from said air as withdrawn from said enclosure in said second adsorber, drying and cooling said third adsorber and removing solvent content from said air as withdrawn from said enclosure in said fourth adsorber; then drying and cooling said first adsorber, removing solvent content from said air as withdrawn from said enclosure in said second adsorber and in said third adsorber, subjecting said fourth adsorber to steam, all in a fourth cycle; and continuously during each of said cycles removing said treated air from two of said adsorbers, adding a portion of fresh air to said treated air, establishing predetermined conditions of temperature and humidity of said treated air, and then returning said air to said enclosure.

3. The method of continuously maintaining predetermined conditions of temperature, humidity and solvent vapor content in the atmosphere of an enclosure wherein said solvent is used comprising, exhausting atmospheric air from the enclosure, removing solvent content from said air in a first adsorber of a bank of adsorbers while simultaneously subjecting a second adsorber to steam, removing solvent from said atmosphere in a third adsorber and drying and cooling a fourth adsorber, all in a first cycle; then removing solvent content of said air as withdrawn from said enclosure in said first adsorber, drying and cooling said second adsorber, subjecting said third adsorber to steam and removing solvent content from said air as withdrawn from said enclosure in said fourth adsorber, all in a second cycle, then subjecting said first adsorber to steam, removing solvent content from said air as withdrawn from said enclosure in said second adsorber, drying and cooling said third adsorber and removing solvent content from said air as withdrawn from said enclosure in said fourth adsorber; then drying and cooling said first adsorber, removing solvent content from said air as withdrawn from said enclosure in said second adsorber and in said third adsorber, subjecting said fourth adsorber to steam, all in a fourth cycle; and continuously during each of said cycles removing said treated air from two of said adsorbers, adding thereto a portion of fresh air substantially less than the returned treated air and establishing predetermined conditions of temperature and humidity of said treated air, and then returning said air to said enclosure.

4. The method of continuously maintaining predetermined conditions of temperature, humidity and solvent vapor content in the atmosphere of an enclosure wherein said solvent is used and comprising, exhausting atmospheric air from the enclosure, removing solvent content from said air in an adsorber of a bank of adsorbers while simultaneously subjecting another adsorber of said bank of adsorbers to steam, removing solvent from said atmosphere in still another adsorber of said bank of adsorbers and drying and cooling yet another adsorber of said bank of adsorbers, all in one cycle; removing solvent content of said air as withdrawn from the enclosure in said first named adsorber, drying and cooling said second named adsorber, subjecting said third named adsorber to steam and removing solvent content from said air as withdrawn from the enclosure in said fourth named adsorber, all in another cycle; subjecting said first named adsorber to steam, removing solvent content from said air as withdrawn from the enclosure in said second named adsorber, drying and cooling said third named adsorber and removing solvent content from said air as withdrawn from the enclosure in said fourth named adsorber; then drying and cooling said first named adsorber, removing solvent contents from said air as withdrawn from the enclosure in said second named adsorber and in said third named adsorber, subjecting said fourth adsorber to steam, all in still another cycle; and continuously during each of said cycles removing said treated air from two of said adsorbers, establishing predetermined conditions of temperature and humidity of said treated air, and then returning said air to the enclosure, and starting and ending the said method in any one of the hereinbefore recited cycles.

E. L. LUÁCES.
